UNITED STATES PATENT OFFICE.

CHARLES G. PERKINS, OF HARTFORD, CONNECTICUT, ASSIGNOR TO THE PERKINS ELECTRIC SWITCH MANUFACTURING COMPANY, OF SAME PLACE.

DESIGN FOR A COVER FOR ELECTRICAL CUT-OUTS.

SPECIFICATION forming part of Design No. 31,044, dated June 20, 1899.

Application filed May 24, 1899. Serial No. 718,120. Term of patent 7 years.

To all whom it may concern:

Be it known that I, CHARLES G. PERKINS, a citizen of the United States, residing at Hartford, in the county of Hartford and State 5 of Connecticut, have invented a certain new and original Design for Covers for Electrical Cut-Outs, of which the following is a specification.

Referring to the accompanying drawings, which form a part of this specification, Figure 1 is an edge view of an electrical cut-out cover that bears the new design, and Fig. 2 represents a plan view of the same.

As shown in the drawings, the leading or 15 material feature of the design consists in a series of grooves, corrugations, or flutes arranged, as shown in Fig. 1, about the cylindrical part of the cover. The cover has a cylindrical part 1, with a hub 2 extending from

the cylindrical part. There is a quarter-curve 20 3 between the cylindrical part 1 and the hub 2, which hub curves from the end of the cylindrical part to its outer smaller end. The series of flutes or grooves 4 in the periphery of the cylindrical part begin a little distance 25 in from one end and extend to the other end of the cylindrical part—that is, they do not extend all the distance across the cylindrical part.

Having described my invention, what I 30 claim as new, and desire to secure by Letters Patent, is—

The design for a cover for electrical cut-outs herein shown and described.

CHARLES G. PERKINS.
